CLAIM

The ornamental design for a connector as shown and described.

DESCRIPTION

FIG. 1 is a top perspective view of a connector, showing the new design;

FIG. 2 is a right side view thereof;

FIG. 3 is a left side view thereof;

FIG. 4 is a front view thereof;

FIG. 5 is a rear view thereof;

FIG. 6 is a top plan view thereof;

FIG. 7 is a bottom plan view thereof; and,

FIG. 8 is a cross-sectional view taken at line 8-8 in FIG. 2. The broken lines depict portions of the connector that form no part of the claimed design.

1 Claim, 8 Drawing Sheets
